(57) **CLAIM**

The ornamental design for computer generated alignment markings for lens blank displayed on a display, as shown and described.

DESCRIPTION

FIG. 1 is a front view of alignment markings of a first embodiment of our design displayed on a display, the broken line drawing of the display, lens blank, and finished lens shape is for illustrative purposes only and forms no part of the claimed design;

FIG. 2 is a front view of the alignment markings of FIG. 1 displayed on the display in a second orientation; and.

FIG. 3 is a front view of the alignment markings of FIG. 1 displayed on the display in a third orientation.
